DESIGN FOR A COMBINED TOWEL BAR AND BRACKET

Myron J. Zimmer, Chicago, Ill., assignor to The Edward Katzinger Company, Chicago, Ill., a corporation of Illinois

Application December 10, 1938, Serial No. 81,698

Term of patent 14 years

To all whom it may concern:

Be it known that I, Myron J. Zimmer, a citizen of the United States, residing at Chicago, in the county of Cook and State of Illinois, have invented a new, original, and ornamental Design for a Combined Towel Bar and Bracket, of which the following is a specification, reference being had to the accompanying drawing, forming part thereof.

Fig. 1 is a perspective view of a combined towel
bar and bracket showing my new design.

Fig. 2 is a front elevational view thereof, the towel bar being shown broken away.

Fig. 3 is an end elevational view.

I claim:

The ornamental design for a combined towel
bar and bracket, as shown.

MYRON J. ZIMMER.
